UNITED STATES PATENT OFFICE.

FRANZ MELAUN, OF CHARLOTTENBURG, GERMANY.

RAIL-JOINT.

SPECIFICATION forming part of Letters Patent No. 732,311, dated June 30, 1903.

Application filed February 11, 1902. Serial No. 93,598. (No model.)

To all whom it may concern:

Be it known that I, FRANZ MELAUN, engineer, a subject of the King of Prussia, German Emperor, residing at 24 Fasanenstrasse, 5 Charlottenburg, Germany, have invented certain new and useful Improvements in Rail-Joints, of which the following is a specification.

A form of fastening for rail-joints, according to which two headed fish-plates over which the wheels run are wedged into a bridge-plate, has already been patented.

My invention differs from the above inasmuch as I employ only a single headed fish-plate in conjunction with a counter fish-plate 15 lying below the heads of the rails, the two fish-plates being wedged into a bridge or bed plate.

My improved rail-joint fastening is illustrated in the accompanying drawings, in which—

Figure 1 is a side elevation of the device, partly in section; and Fig. 2, a cross-section on the line E F of Fig. 1.

The rail ends, the tread of which for a certain distance is interrupted by removal of the rail-heads or by retreating the ends of the rails from one another, are connected by fish-plates *d* and *e*. The headed fish-plate *d*, 25 which carries the load, has a laterally-overhanging head which fills up the gap extending over the full breadth of the tread, so that the load of the wheels is fully taken up by it. The second fish-plate *e* lies below the 30 heads of the two rail ends and below the head of the fish-plate *d*. The two fish-plates *d* and *e* have horizontal bases which are wedged between the inclined surfaces *f* of the bridge-plate *g*. In this manner all parts of the joint 35 are firmly and automatically connected together simply by the pressure of the wheels passing over it, as will now be explained. When the vertical pressure of the wheel acts upon the headed fish-plate, the latter tends

to slide down the inclined surface *f* of the 45 plate *g*, giving rise to a horizontal pressure laterally on the rail ends. This lateral pressure is transmitted by the rail ends to the second fish-plate *e*, and as the latter bears against the second inclined surface *f* of the 50 plate *g* and above lies against the head of the headed fish-plate the pressure of the wheel, owing to the wedging action, will effect an exceedingly firm connection between the parts *d* *g* *e*. The parts thus extremely intimately pressed together merely by the pressure of the wheel and by reason of the wedging action, and therefore independently of bolts, form a hollow girder supported by one or two sleepers, in which girder also the rail 55 ends are very firmly held. The latter, however, can nevertheless respond to the unavoidable expansion and contraction of the rails in the direction of their length and can also take up inclined positions in the vertical 60 plane rendered necessary by the elastic sinking motions of the sleepers.

Having thus described my invention, what I claim as new, and desire to secure by Letters Patent, is—

The combination of a rail-joint fastening, comprising a headed fish-plate filling up the gap extending over the full breadth of the tread between two rails, and alone sustaining the load of the wheels, and a counter fish-plate lying below the head of rails and headed fish-plate, with a bridge-plate supported by one or two sleepers, in which plate the said fish-plates fit with wedging action, all substantially as and for the purposes hereinbefore set forth.

Signed at Berlin this 27th day of January, 1902.

FRANZ MELAUN.
